UNITED STATES PATENT OFFICE.

ABRAHAM J. MANNY, OF ST. LOUIS, MISSOURI.

CANE-MILL.

SPECIFICATION forming part of Letters Patent No. 282,339, dated July 31, 1883.

Application filed May 24, 1880. Renewed February 8, 1883. (No model.)

To all whom it may concern:

Be it known that I, ABRAHAM J. MANNY, of the city of St. Louis, and State of Missouri, have invented certain new and useful Improvements in Cane-Mills, of which the following is a full, clear, and exact description, reference being had to the accompanying drawings, forming part of this specification.

My improvement relates to that form of cane-mills having horizontal pressure-rollers, and to cane-mills having a feed-roller, a crushing-roller, and a delivery-roller arranged horizontally in triangular form, by which the cane is twice subjected to pressure in one passage through the mill—first between the feed-roller and the crushing-roller, and, second, between the delivery-roller and the crushing-roller. In my improvement the feed-roller and delivery-roller are above instead of beneath the crushing-roller, thereby securing an angle for presentation of the cane at a more convenient height.

My invention consists in the construction hereinafter described, and pointed out in the claims.

In the drawings, Figure 1 is a front elevation of the mill. Fig. 2 is a longitudinal section, showing the main roll and central brace-plate in side view. Fig. 3 is a transverse section at $x x$, Fig. 2, showing an inside view of one of the side plates. Fig. 4 is a perspective view of the feed-plate.

The frame of the mill is formed of the four plates—the bottom plate, A, the top plate, B, and the two end plates, C C. The bottom plate, A, is made of curved form and arranged with its concave face upward, and is provided with ears $a a a a$ —one at each end and one at each side—by which to secure and support it upon a frame-work or posts; also, with ears $a' a' a' a'$ —two at each side—to receive the frame-bolts K, and with two pairs of transverse ledges, $a^2 a^3 a^2 a^3$, on its inner face, between the ledges $a^3 a^3$ of which is formed the juice-basin D. In the center of the basin is the hole d, through which the juice is discharged. One end of the bottom plate, A, is extended beyond the end plate to form a support for the lower bearing, e, of the upright shaft E, to the upper end of which the sweep-cap F is attached, and on which is keyed the

large bevel-wheel G, gearing into the bevel-pinion H on the shaft of the main roll I. The top plate, B, is also of curved form and arranged with its concave face downward, and is provided with ears $b b b b$ —two at each side—to receive the frame-bolts, and two pairs of transverse ledges, $b' b' b' b'$, on its inner face one end of said top plate also extending, beyond the end plate to form the support for the top gearing, e' , of the upright shaft E.

The end plates, C C, have their top and bottom edges fitted tightly in the groove formed between the transverse ledges $b' b' b' b'$ and $a^2 a^3 a^2 a^3$ in the top and bottom plates, respectively, and carry the journal-bearings for the shafts i and j j of the pressure-rolls I and J J. The frame of the mill is bound together by the four corner bolts K, which pass through the ears $a' a' a' a'$ in the bottom plate and $b b b b$ in the top plate.

The feed-plate L and the discharge-plate M, each of which fills (one on each side) the space between the bottom plate, A, and the top plate, B, have each, both upon its upper and lower edges, ledges N, with square ends or shoulders N', and on their inner faces each has two transverse grooves, n. The top plate, B, and the bottom plate, A, have each, one upon its lower and the other upon its upper edge, respectively, a recess or rabbet-groove, O, having square ends or shoulders, into which the ledges N, with the square ends of shoulders N', fit closely, and the outer edges of the end-plates, C C, also fit closely into the grooves n of the feed-plate L and discharge-plate M. The frame of the mill is thus securely braced longitudinally. The plates L and M are interchangeable for the purpose of changing the direction of feed when it is desired to feed from the left side instead of the right side.

The inside angular brace-plate, P, has square ends fitting against the end plates, C C, and a straight top resting against the inside of the top plate, B, and is provided with projections p, formed to fit closely in the recesses p' in the top plate, B, and the end plates, C C, thus affording an additional longitudinal brace to the mill.

The conducting-ledges r r, on the inner faces of each of the end plates, C C, extend from above and outside the upper shaft-bearings,

their lower ends approaching each other and connecting with the recesses or openings r' in the lower ends of the end plates, C C, and the ledges $a^2 a^3 a^2 a^3$, thus conducting the waste oil 5 from all the journals outside the juice-basin.

The main roll I has juice-retaining disks S S interposed between its ends and its journal-bearings to convey the juice, as it flows off the ends of the roll, into the juice-basin D, and to 10 prevent the juice from running along the shaft i and escaping with the waste oil.

The feed-plate L has orifice l , through which the cane is fed, and at the lower side of which is formed the rest-bar l' , extending across its 15 mouth, serving to hold the canes up to and direct their entrance between the rolls, and having its outer face rounded to conduct any juice that may flow back upon it into the juice-basin. The feed-plate L is provided, also, with 20 the juice-apron T, turned upward and outward in the direction from whence the cane is fed, its upper edge having a sharp corner over which the cane is fed and on which it rests, its inner face being inclined into the juice-basin 25 D, to convey into said juice-basin any juice which may follow back and drip from the outer face of the rest-bar l' , or flow back upon the uncrushed stalks.

The horse is attached to the end of a sweep, 30 bolted to the cap F, that is keyed to the upright shaft E, which carries the large bevel-wheel G, gearing into the bevel-pinion H on the shaft of the main roll I, which shaft carries on its other end the spur-gear U, gearing 35 into and driving the spur-wheels V V and the rolls J J. The rolls J J have at their ends peripheral flanges J' J', which lap over the ends of the main roll I and serve to prevent the lateral escape of the canes.

40 I claim as my invention—

1. In a cane-mill, the combination of three pressure-rollers—namely, a feed-roller, a crushing-roller, and a delivery-roller—arranged horizontally and in triangular form, 45 with the feed-roller and the delivery-roller above the crushing-roller, substantially as herein shown and described.

2. In a cane-mill, the combination of the three pressure-rollers arranged horizontally 50 and in triangular form, and provided with suitable gear-wheels, the feed-roller and the delivery-roller being above the crushing-roller, the bevel-wheel upon the upright shaft, and the bevel-pinion on the shaft of the crushing-55 roller, substantially as herein shown and described.

3. In a cane-mill, the combination of the

three pressure-rollers, arranged horizontally and in triangular form, the feed-roller and delivery-roller being above the crushing-roller, 60 and the lower or crushing roller having juice-disks at its ends, substantially as herein shown and described.

4. In a cane-mill, the combination of the three pressure-rollers, arranged horizontally 65 and in triangular form, the feed-roller and delivery-roller being above the crushing-roller, and having peripheral flanges at their ends, substantially as herein shown and described.

5. In a cane-mill, the combination of the 70 pressure-rollers, horizontally arranged, the bottom plate and the end plates, the latter having conducting-ledges on their inner faces, and openings communicating with the bottom plate and connecting with said ledges, 75 substantially as herein shown and described.

6. In a cane-mill, the combination of the pressure-rollers, horizontally arranged, the feed-plate and the discharge-plate interchangeable with each other, substantially as herein 80 shown and described.

7. In a cane-mill, the combination of pressure-rollers, horizontally arranged, a feed-plate and a discharge-plate, each formed with projecting ledges, each having square ends on its 85 edges and grooves on its inner face, a top plate and a bottom plate, each formed with recesses of a width, depth, and length to receive said ledges, and end plates formed with edges of a width to enter the grooves in the feed and discharge plates, substantially as herein shown and described.

8. In a cane-mill, the combination of pressure-rollers, horizontally arranged, the end plates, top plate, and the inside angular brace 95 plate, formed at its ends and top to bear in the end plates and top plates, respectively, substantially as herein shown and described.

9. In a cane-mill, the combination of the pressure-rollers, horizontally arranged, the 100 juice-basin, and a feed-plate formed with a rest-bar extending across and forming the lower edge of its mouth, and having its lower edge within the inner edge of the juice-basin, and the juice-apron having its upper edge on 105 a line with the lower edge of the feed-opening, and its inner face extending into the juice-basin, substantially as herein shown and described.
